ELECTRIC CABLE SYSTEM

Charles E. Bennett, Ridgewood, N. J., assignor to
The Okonite-Callender Cable Company, Incorporated,
Paterson, N. J., a corporation of New Jersey

Original application December 7, 1935, Serial No.
53,344. Divided and this application August
13, 1936, Serial No. 95,821

4 Claims. (Cl. 247—3)

This invention is directed to electric distribution systems particularly well adapted for use in connection with the distribution of power for street lighting, house lighting and other domestic or commercial loads. The invention provides a construction wherein the cable conductors and the transformers for the system are installed in a pipe line filled with an insulating fluid such as oil in which the insulated conductors and transformers are immersed, the oil in which the transformers are immersed being the same oil in which the cable conductors are immersed. The entire system is buried in the ground and means are provided for dissipating the heat generated in the system having particular reference to the heat generated by electric losses in the transformers. This insures best operating conditions at all times.

This application is a division of my copending application Serial No. 53,344, filed December 7, 1935.

In the drawing:

Fig. 1 is a view in elevation, more or less diagrammatic in character, of a cable system embodying my invention; and

Fig. 2 is a part sectional elevational view of the construction employed in Fig. 1.

Referring to the drawing in detail, I designate a pipe line adapted to be buried in the ground which encloses the cable conductors 2 and transformers 3 of the system. It will be observed from the drawing that that part of the pipe line in which the transformers 3 are mounted is lowered with respect to the level or plane of the main part of the pipe line.

The transformers, as will be seen from Fig. 2, are mounted in the pipe line in suitable brackets 4, these brackets in the construction shown functioning as baffles for the oil or other insulating fluid 1 with which the pipe line is filled. The cable conductors 2 and transformers 3 are immersed in this fluid, the fluid is preferably maintained under static pressure sufficiently high materially to increase its dielectric strength, for example, five atmospheres minimum, and the transformers are immersed in the same oil or other fluid as the cable conductors.

The baffles 4 are provided adjacent their lower edges with suitable openings or ports 8 to permit of movement of the fluid 1 in the pipe line from the outer side of the baffle plates to the transformer side.

At the upper part of the baffles 4 I provide short lengths of pipe 9, these pipes lying within the pipe line and extending a short distance

outwardly from the transformer locations. The pipes terminate within the pipe line, as shown at 10, at a suitable distance from the transformers 3.

It will be quite apparent that in this embodiment of my invention a thermal siphon effect is obtained, the oil or other fluid 1 immediately about the transformers 3 and which is heated by the electric losses in the transformers moves outwardly away from the transformers through the pipes 9, the heat in this oil being dissipated by the pipes 9 being immersed in the relatively cooler oil in the pipe line remote from the transformers, the oil returning to the oil in the pipe line at the ends of the pipe 9 and flowing back to the transformers again.

It will be apparent that the present invention provides an electric distribution system in which the conductors and transformers of the system are enclosed in a pipe line containing oil or other insulating fluid in which the conductors and transformers are immersed, the transformers being immersed in the same oil as the conductors, means being provided for permitting of movement of the insulating fluid away from the transformers for dissipation of the heat generated by electric losses in the transformers.

What I claim is:—

1. A buried electric distribution system comprising in combination a pipe line, insulated cable conductors in the pipe line, a transformer in the pipe line electrically connected to said conductors, an insulating fluid in the pipe line in which said conductors and transformer are immersed, baffles in the pipe line at each side of the transformer, provided adjacent the bottom with means for permitting of the movement of the insulating fluid from the outer side of the baffles to the transformer side of the baffles, and open-ended pipes passing through said baffles adjacent the top thereof and extending away from the baffles, said pipes being enclosed by and terminating within said pipe line.

2. A buried electric distribution system comprising in combination a pipe line, insulated cable conductors in the pipe line, a transformer in the pipe line electrically connected to said conductors, an insulating fluid in the pipe line in which said conductors and transformer are immersed, said fluid being under superatmospheric static pressure, baffles in the pipe line at each side of the transformer, provided adjacent the bottom with means for permitting of the movement of the insulating fluid from the outer side of the baffles to the transformer side of the baffles, and

open-ended pipes passing through said baffles adjacent the top thereof and extending away from the baffles, said pipes being enclosed by and terminating within said pipe line.

- 5 3. A buried electric distribution system comprising in combination a pipe line, insulated cable conductors in the pipe line, a transformer in the pipe line electrically connected to said conductors, an insulating fluid in the pipe line in which said 10 conductors and transformer are immersed, the pipe line at the transformer being lower than the main part of the pipe line, baffles in the low part of the pipe line at each side of the transformer, said baffles being provided adjacent the 15 bottom thereof with means for permitting of movement of the insulating fluid through the baffles toward the transformer, and open-ended pipes passing through said baffles adjacent the top thereof and extending away from the baffles, 20 said pipes being enclosed by and terminating within said pipe line.

4. A buried electric distribution system comprising in combination a pipe line, insulated cable conductors in the pipe line, a transformer in the pipe line electrically connected to said conductors, an insulating fluid in the pipe line 5 in which said conductors and transformer are immersed, said fluid being under superatmospheric static pressure, the pipe line at the transformer being lower than the main part of the pipe line, baffles in the low part of the pipe line at each 10 side of the transformer, said baffles being provided adjacent the bottom thereof with means for permitting of movement of the insulating fluid through the baffles toward the transformer, and open-ended pipes passing through said baffles 15 adjacent the top thereof and extending away from the baffles, said pipes being enclosed by and terminating within said pipe line.

CHARLES E. BENNETT. 20
